UNITED STATES PATENT OFFICE

2,255,071

DISK MILL

John Marco, Philadelphia, Pa., assignor to Marco Company, Inc., Philadelphia, Pa., a corporation of Pennsylvania

Application May 4, 1939, Serial No. 271,786.

3 Claims. (Cl. 83—8)

My invention relates to new and useful improvements in grinders, disintegrators, emulsors or the like and more particularly to the type of machine wherein a material in more or less liquid form is fed under pressure to the grinding, disintegrating or emulsifying elements.

Still another object of the invention resides in the provision of a machine wherein the material to be treated is fed to the grinder, disintegrator or emulsifier by means of a spiral shaft.

A still further object of the invention resides in the provision of a grinding, disintegrating or emulsifying device in which a stationary element and a rotating element are provided, the contacting or working faces of which are each provided with series of radially arranged shearing elements, varying in length, depth and position with respect to the faces upon which they are formed.

A still further object of the invention resides in the provision of a grinding, disintegrating or emulsifying device formed of stationary and rotating elements, the stationary element being provided with a chamber for either cooling or heating the materials being processed.

Still another object of the invention resides in the provision of a thrust block operating in connection with the rotor for guiding, aligning or piloting said rotor in its action against the stationary element of the grinding device or stator.

And a still further object resides in the provision of an improved form of thrust bearing housing within said thrust block for facilitating the adjustment of said block.

A still further object of the invention resides in the provision of an indicating dial with minute divisions provided thereon whereby fine adjustments may be made of the grinder, at the will of the operator.

With these and numerous other objects in view, my invention consists in the novel features of construction hereinafter referred to and more particularly pointed out in the specification and claims.

In the accompanying drawings forming part of this application,

Figure 1 is a vertical section through my improved grinder, disintegrator, emulsor or the like attached to a pump, with parts shown in elevation,

Figure 2 is a front elevation thereof,

Figure 3 is a vertical section as seen on the line 3—3 of Figure 1, looking in the direction of the arrows,

Figure 4 is a similar view as seen on the line 4—4 of Figure 1, looking in the direction of the arrows,

Figure 5 is a similar view as seen on the line 5—5 of Figure 1, looking in the direction of the arrows,

Figure 6 is a similar view as seen on the line 6—6 of Figure 1 looking in the direction of the arrows,

10 Figure 7 is a vertical section as seen on the line 7—7 of Figure 1,

Figure 8 is a horizontal section as seen on the line 8—8 of Figure 2, with parts of the pump shown in dotted lines, and parts of the device removed,

15 Figure 9 is a fragmentary plan view, partly in section, showing the relationship of the driving shaft to the rotor,

Figure 10 is a fragmentary perspective view, 20 partly in section on the rotor showing particularly the grooved face thereof, and

Figure 11 is a side elevation of a complete machine embodying my pump structure and my improved grinder, disintegrator and emulsor.

25 I have found in the development of my various apparatus, including pumps, homogenization grinders, disintegrators and emulsifying apparatus in general, that the present-day devices are incapable of adaptation to various and numerous industries, that is, incapable of versatility. Such machines generally known to the trade today have been found lacking in that they are incapable of the interchange of parts so as to be used effectively in all and numerous industries where grinding, disintegration, emulsification, blending, etc., becomes necessary. It is the purpose of my invention to provide a machine so constructed that elements may be readily and quickly removed and corresponding elements substituted therefor, whereby the machine

30 may be used in every possible industry where the necessity arises for grinding, disintegrating, emulsifying, homogenizing, blending, etc.

For instance, the machine embodying my invention is particularly well adapted for use in the general food industry, where fruits, vegetables, confections and the like require, in their manufacture, grinding, emulsification and the like; and likewise, the same is well adapted for

40 use in the manufacture of chemicals, medicines and pharmaceutical preparations, where ingredients thereof require grinding or emulsification; and further, this machine is capable of effective use and adaptation in the industry involving the manufacture of asphaltum or other petroleum

45 50 55

products; and still further is particularly well adapted for use in the dairy industry in the manufacture of cheese, ice cream, flavors, etc. I have personally operated this apparatus successfully in the processing of cranberries, including skin and seed, for jellies, sauces, etc.; with strawberries, blackberries, raspberries, prunes, apples, peaches, skin and pulp, made into a fruit puree where neither skin nor seed is visible; with oranges, lemons, and different citrus fruits including pulp, skin and juice, made into a paste suitable for industries where fresh fruit flavors are adaptable; in stabilizing peanut butter to the state where oil does not bleed out; in the making of vanolin and cocoabutter, mixing the vanilla bean with numerous confections; in controlling viscosity of various condensed milks; in treating chocolate to omit blooming (changing color); emulsifying wax with water definitely; improving the penetrable quality of cold creams, hand lotions, zinc ointments, etc. and various other medicinal compounds such as cream of carbonate, milk of magnesia, etc.; in the making of asphaltum emulsions to obtain viscosity suitable for numerous applications; in treatment of spinach, peas, carrots, barley and a number of other vegetables for emulsification to a point adaptable for baby feeding; in handling bone-charcoal emulsified for the treatment in sugar refining; treating mustard seeds, vinegar, spices, etc. in one operation preparatory to packaging; in the manufacture of automobile polishes that contain diatomaceous earth; in making abrasives with wax bases successfully emulsified to set in solution; producing waterproofing and softening compounds for textiles; in making of fondante creams, fudges, and syrups improved to a point where a lesser crystallization formation occurs, and in handling of numerous other materials and compounds. This illustrates the versatility of the machine in its many applications to use. I find that in the other so-called apparatus alleged to have qualifications to accomplish some of these aforementioned results are not as well adaptable for the purposes as mine and are incapable in one machine of accomplishing all the results claimed by me.

In the accompanying drawings, the numeral 1 designates the forward end of a pump structure, the details of which are immaterial insofar as the present invention is concerned, but which may be found fully illustrated and described in my copending application Serial No. 235,509, for Homogenizer and pump. In this connection, it is emphasized that my invention is capable of application to a specific pump structure now known to the trade, thus enabling the present invention to be readily and quickly adapted thereto, or other grinding, disintegrating, emulsifying, homogenizing or similar apparatus, as covered in other copending applications of mine, to be substituted therefor, although the invention may be applied to some other pump structure that is constructed and fitted to accomplish the purpose, if there be any such existing.

The numeral 2 designates the driving shaft which in this instance is a driving shaft projecting from the pump structure. This drive shaft is extended beyond the pump structure as shown by the numeral 3 and is designed with spiral grooves 4 for the purpose of feeding the material being treated to my improved grinding apparatus. This extended portion 3 of the drive shaft is housed within the tubular portion of a head 5 which is bolted to the face of the pump structure 1

through the medium of the bolts 6. Bolted to the outer face of the head 5 through the medium of the studs 7 are the cover plate 8, seal plate 9, grinder housing body 10 and stator plate 11, the latter abutting directly against the outer face of said head 5, as clearly shown in Figure 1 of the drawings. Interposed between the inner face of the plate 8 and the seal plate 9 is the seal 12 which surrounds the thrust block 13, the latter aligning, adjusting and supporting a rotor 14 in position against the outer face of the stator plate 11. This rotor 14 is splined on the extension 3 of the drive shaft and said thrust block 13 retains said rotor in position against the stator plate as will be hereinafter more particularly set forth. Threaded into the outer face of the rotor 14 is the seal plug 15 to prevent the seepage of material therefrom.

The thrust block 13 supports at its outer end a thrust bearing 16 of conventional form to facilitate adjustment allowing the thrust block to rotate with said rotor and this bearing is held in place through the medium of the adjusting cap 17 which is internally threaded and engaged with external threads on the extended tubular portion of the cover plate 8. A hand bar 18 is provided on the cap 17 to enable ready adjustment thereof by the operator.

Mounted on the outer face of the vertical portion of the cover plate 8 is a dial 18a having thereon numerous division markings which cooperate with a pointer 19 carried on the peripheral face of the cap 17 at its innermost edge. Through this medium, the cap may be adjusted to definite positions and there held by an adjusting lock screw 20 which projects through the cap 17 and engages the horizontal extension of the cover plate 8, as clearly shown in Figure 1. By this dial and pointer arrangement, aforesaid, the operator having found a successful result attained with a certain adjustment of the elements in the treatment of certain materials, may make note thereof and thereafter adjust the cap to the same position for all future operations in the treatment of that same material for the same purpose.

The head 5 which is formed with a tubular housing is provided with an intake port 21 through which the material is fed by the pump structure from whence it is fed, as aforesaid, to the grinding or emulsifying structure. The inlet port, however, communicates with a bore 22 which extends longitudinally through the horizontal tubular portion of the head 5 to enable the ready cleansing of the inlet port. The outer end of this bore 22 adjacent the stator plate 11 is covered with a gasket 23 held in place by said stator plate.

The grinder housing 10 is provided with an outlet port 24 and in view of the particular arrangement of parts, with the bolts 7 uniformly spaced, this housing may be adjusted in any position so that said outlet port 24 may be directed to any desired angle with respect to the apparatus.

The outer face of the stator plate 11 is provided with a specific means for grinding, shearing, disintegrating, emulsifying, or homogenizing the material which is treated in this apparatus. The means involves several series of elements to accomplish the desired result, the first of which, that is, the elements nearest the axis of the apparatus, embodies radial grooves 25 in the stator plate 11 which are substantially V-shaped in cross-section and taper smaller

toward their outer ends. Interposed between the pairs of grooves 25 and also arranged radially with respect to the stator plate are the additional grooves 26 which are arcuately formed in longitudinal section. These grooves 26 are materially shorter in length than the grooves 25, as clearly shown in Figure 10 of the drawings.

Surrounding the grooves 25 and 26 and forming an arc thereabout, I provide the diagonal grooves 27 which are directed at a substantially 45° angle and are arcuately formed in cross-section as shown in Figure 10. The face of the stator plate 11 adjacent the peripheral edge thereof is further provided with an additional set of grooves 28 which are finer in dimension than the grooves 27 and are directed at substantially a 45° angle opposed to the angle of the grooves 27, as clearly shown in Figure 10. These grooves 28 are substantially rectangular in cross-section.

The inner face of the rotor 14 contacting with the outer face of the stator plate is likewise grooved, serrated or milled exactly as the outer face of said stator plate, just described, and for convenience the grooves of said rotor are referred to, respectively, as 25a, 26a, 27a and 28a. While the grooves 27 and 28 of the stator plate and the grooves 27a and 28a of the rotor appear to be disposed respectively at the same angle, it will be seen that when the faces of said rotor and stator plate are in abutting relation, the grooves of one element will be disposed at cross-angles to the similar grooves of the opposed element, thereby obtaining a true shearing action on the material being processed. Obviously, material passing through the spiral grooves of the driving shaft 3 will be forced under pressure between the faces of the stator plate and rotor for treatment by the shearing action of the grooves in the contacting faces of said elements, as the rotor revolves, and the material thus treated after passing between said elements will flow from the chamber within the grinder housing through the outlet port 24. It may be here stated that the driving shaft 3 rotates counter-clockwise when viewed as shown in Figure 7 and the spiral grooves 4 in said shaft are of such a pitch and angle that during rotation of the shaft in this direction the material fed from the pump to this shaft will be forced forwardly to the grinding elements, regardless of the viscosity or density of said material.

The stator plate 11 is provided with a liquid-receiving chamber 29 which is provided with an inlet port 30 and an outlet port 31 whereby a fluid, either hot or cold, may be supplied thereto, according to the required process.

From the foregoing description of the construction of my improved apparatus, the operation thereof will be readily understood. It will be seen that the structure is such that the various elements may be quickly and readily removed at the will of the operator and particularly adapted for ready removal each day when work therewith has been completed, so that each and

every part and/or element of the device may be cleansed, as is necessary and required under the law where foods and drugs are being processed.

It will be further seen that I have provided a simple, inexpensive and efficient means for carrying out the various objects of my invention, and while I have particularly described the elements best adapted to perform the functions set forth, various changes in form, proportion and in the minor details of construction may be resorted to without departing from the spirit or sacrificing any of the principles of the invention.

What is claimed is:

1. In a grinder, a body having a chamber thereto provided with an inlet and an outlet, a rotary shaft extending into said chamber, a rotor in said chamber carried by said shaft with one side face confronting a face of the stator, the confronting faces of the stator and the rotor being each formed with a row of radially extending grooves V-shaped in cross section and tapered to points at their outer ends, other radially extending grooves between outer portions of the V-shaped grooves and having longitudinally curved inner walls, a concentric row of grooves extending diagonally from outer ends of said grooves and having transversely curved inner walls, and an outer concentric row of grooves extending diagonally in a direction opposite that of the said diagonal grooves and being rectangular in cross section.
2. In a grinder including a chamber having an inlet and an outlet, a stator in the chamber, and a rotor in the chamber rotatable about an axis concentric to the center of the stator; the stator and the rotor having confronting faces one of which is formed with a row of radially extending grooves V-shaped in cross section and tapered toward their outer ends, other radially extending grooves between outer portions of the tapered grooves and having longitudinally curved inner walls, a concentric row of grooves extending diagonally from outer ends of the aforesaid grooves and having transversely curved base walls, and an outer concentric row of grooves extending diagonally in a direction opposite to that of the first mentioned diagonal grooves and being rectangular in cross-section.

3. In a grinder including a chamber having an inlet and an outlet, a stator in the chamber, and a rotor in the chamber rotatable about an axis concentric to the center of the stator; the stator and the rotor having confronting operating faces one of which is formed with a concentric row of radially extending grooves tapered toward their outer ends, a second row of radially extending grooves located between outer portions of the tapered grooves in spaced relation thereto, a concentric row of grooves extending diagonally from outer ends of the aforesaid grooves, and an outer concentric row of grooves extending diagonally in a direction opposite to that of the first mentioned diagonally extending grooves.

JOHN MARCO
